UNITED STATES PATENT OFFICE

JAMES M. COUGHLIN, OF WILKES-BARRE, PENNSYLVANIA

COVER FOR SHIPPING DRUMS

Application filed May 13, 1930. Serial No. 452,011

This invention relates to a cover for shipping drums of the type disclosed, for example, in Patent 1,834,343, dated March 23, 1920.

Drums used for shipping purposes are usually formed of light steel, one head of the drum being formed with an opening and with a cover or closure for the opening.

Considerable difficulty has been experienced in preventing leakage of the contents of the drum between the cover and the wall of the opening in which it is seated. Another problem has been to prevent seepage of water into the drum between the cover and the wall of the opening.

15 It is an object of the present invention to provide a drum closure having none of the disadvantages heretofore mentioned.

It is another object to provide a closure which can be held in place securely by means 20 of turn buttons or lugs as heretofore, or by crimping.

With the foregoing and other objects in view which will appear as the description proceeds, the invention resides in the combination and arrangement of parts and in the details of construction herein described and claimed, it being understood that changes in the precise embodiment of the invention herein disclosed may be made within the scope of 30 what is claimed without departing from the spirit of the invention.

In the accompanying drawing the preferred form of the invention has been shown.

In said drawing

35 Figure 1 is a plan view of a drum provided with a closure such as constitutes the present invention.

Figure 2 is a central section therethrough on line 2—2, Figure 1, a portion of the cover being shown crimped into locking engagement with the head.

Referring to the figures by characters of reference, 1 designates the head of a drum 2 provided with a central circular opening 3 surrounded by a continuous upstanding flange 4. The upper edge of the flange is rolled outwardly to form an annular bead 5 which extends above the plane occupied by the marginal portion of the head 1. A circular groove 6 is pressed into the outer face

of the head and is concentric with flange 4.

The cover comprises a sheet metal disk 7 having a concentric inverted channel 8 pressed or otherwise formed therein and located where it will receive flange 4 and bead 5 when the cover is forced into closing position. The marginal portion of the cover indicated at 9 is adapted to rest on the head 1 and has its edge bent to form an annular bead 10 located where it can be seated in the 55 groove 6.

If desired lugs or buttons 11 can be pivotally connected to the head 1 where they can be turned into and out of lapping engagement with the marginal portion 9 of the cover. 60

After the drum has been filled with material to be shipped the cover is placed so that bead 5 can enter the inverted channel 8. The cover is then forced tightly to its seat until its marginal portion 9 bears against head 1 70 and bead 10 fits snugly in groove 6. By turning the buttons or lugs 11 to the positions shown, the cover will be held in place securely. If preferred, however, the outer wall of the inverted channel 8 can be pressed inwardly, as by crimping, so as to underlie the bead 5 and thus securely fasten the cover to the head. Either or both of these means of fastening may be employed. 75

It will be noted that when the cover is in 80 place any water that might be trapped upon the head 1 will not drain into the drum, because the bead 5 is supported above the level of the margin of the head and the water would, therefore, drain over the margin. 85

The closure herein described constitutes an efficient seal which will prevent both leakage from the drum and seepage of moisture into the drum.

What is claimed is:

1. A drum head having an opening and a groove concentric with the opening, a flange extending outwardly from the head and surrounding the opening, said flange projecting above the plane occupied by the marginal 95 portion of the head, a cover insertable into the space defined by the flange and having an inverted annular channel for the reception of the flange, the marginal portion of the cover forming an annular flange adapted to 100

rest flat on the head and surround the flange on the head, and means on said portion for seating in the groove.

- 5 2. A drum head having an opening, an outstanding flange surrounding the opening, an annular bead on the flange, a cover having an inverted annular channel for receiving the flange and bead, one wall of the channel underlying the greater portion of the bead to fasten the cover to the head, and an annular bead on the cover, there being a groove in the head for the reception of the bead.
- 10

15 In testimony that I claim the foregoing as my own, I have hereto affixed my signature.

JAMES M. COUGHLIN.
